(57) **CLAIM**

The ornamental design for a cap assembly, as shown and described.

DESCRIPTION

FIG. 1 is a front perspective of a cap assembly in accordance with the present disclosure;

FIG. 2 is a front view of a cap assembly in accordance with the present disclosure;

FIG. 3 is a back view of a cap assembly in accordance with the present disclosure;

FIG. 4 is a side view of a cap assembly in accordance with the present disclosure;

FIG. 5 is a top view of a cap assembly in accordance with the present disclosure; and,

FIG. 6 is a bottom view of a cap assembly in accordance with the present disclosure.

The broken line periphery surrounding the bottom edge of the cap assembly defines the bounds of the claim and forms no part thereof. All areas adjacent to shaded surfaces and the broken line features forming boundaries to the claim surrounding those areas depict environmental subject matter that forms no part of the claim.
